[57] CLAIM

The ornamental design for a tote, as shown and described.

DESCRIPTION

FIG. 1 is a front elevational view of a tote showing my new design; the rear elevational view being a mirror image thereof;

FIG. 2 is a left side elevational view thereof; the right side elevational view being a mirror image thereof;

FIG. 3 is a top plan view thereof; and,

FIG. 4 is a bottom plan view thereof.

FIG. 1

FIG. 2

FIG. 3

FIG. 4
